**NON-VOLATILE MERCAPTAN AND HYDROXY-
AMINE IMPREGNATED END WRAP AND
METHOD OF USE**

Robert S. Moore, Wyoming, Ohio, assignor to The Procter & Gamble Company, Cincinnati, Ohio, a corporation of Ohio

Application October 7, 1957, Serial No. 688,682

12 Claims. (Cl. 132—7)

This invention relates to cold waving of hair. More particularly it relates to permeable sheets impregnated with keratin-reducing compositions.

The so-called "cold permanent waving" of hair is in part accomplished by contacting the hair with some chemical composition which will soften and plasticize it without the use of heat. According to the present understanding in the art such chemical compositions reduce the keratin structure of the hair, thereby breaking disulfide linkages present in the keratin. While the reduced hair is held in a desired configuration the disulfide linkages are restored by an oxidation step thereby tending to hold the hair tresses in the new configuration.

The advantages of cold permanent waving and the disadvantages of waving processes which require heat are well known. Cold waving lotions have been developed in the art which eliminate the need for the complicated heating arrangements, the long treating and waving time and the risk of hair damage from the heat waving processes. Nevertheless, cold waving processes have certain disadvantages.

In commonly used prior art cold waving processes the hair is saturated with a keratin-reducing solution and wound around curlers or other suitable devices. After sufficient time has elapsed to effect desired hair reduction, the hair is rinsed and neutralized by chemical or air oxidation. The manipulation of hair saturated with such reducing solutions is messy and difficult. Some irritation to the hands may result from continued contact with the solution, if the time required for winding the hair on curlers is excessive, or from frequent uses of the solution.

In another prior art process the hair tresses are wound about curling devices, and a keratin-reducing solution is then poured over the wound tresses or introduced onto the outside of the tresses in some manner. When this process is used, it is difficult to obtain a uniform saturation of the air. The outside of a wound tress will receive a heavy concentration of the lotion, while the portion of the hair inside a wound curl will receive a much smaller amount. As a result, portions of the hair may be damaged by the too high concentration and other parts of the hair may not be waved at all because they are not contacted by sufficient lotion to break the disulfide bonds.

It has now been found that keratin-reducing compositions may be applied to the hair easily and conveniently by means of the impregnated sheets of this invention. The impregnated sheets containing the components necessary for hair reduction are placed in contact with hair tresses, and the tresses are wound about curlers. The wound curls are saturated with water which dissolves the keratin-reducing composition from the impregnated sheets and the solution becomes dispersed throughout the curl to react with the keratin of the hair. After the disulfide linkages are broken the action of the reducing composition is stopped and the disulfide linkages are reformed by rinsing the hair and neutralizing it either chemically or by air. The provision of impregnated sheets which are effec-

2

tive, safe, economical, practical and easy to use is not without problems and difficulties.

Accordingly, it is one of the objects of this invention to provide a novel, improved and simple means for waving hair.

Another object is to provide impregnated sheets suitable for cold hair waving having the proper concentration and type of hair waving chemicals whereby the sheets are stable, safe and effective and so pliable and non-brittle that the sheets can be easily manufactured and used.

A further object is to reduce the hand and skin irritation associated with prior art cold waving procedures.

In general, this invention comprises a thin, pliable permeable sheet impregnated with a substantially non-volatile, water-soluble, keratin-reducing composition which consists essentially of a mercaptan and a substantially non-volatile, hydroxyamine alkaline buffering material in a sufficient amount to maintain the composition at a pH of between 8.5 and 10 when the composition is dissolved in water and is in contact with the hair.

The drawing represents a series of similar hair tresses waved under conditions varying in intensity as indicated by the arbitrary value assigned to each tress, more fully described hereinafter in Example IV.

25 The term "impregnated" as used in connection with the sheets of this invention is intended to include a coating of the keratin-reducing composition on the surface of the sheet, and a coating on individual fibers as well as the filling up of interstices between the fibers.

30 The term "pliable" as used in connection with the sheets of this invention means that the sheets can easily be bent and rolled with hair tresses into curls of ordinary size and tightness without the sheets cracking or breaking. Moreover, the pliable sheets should not be so resilient that they 35 cannot be easily rolled and the curls held in place by the common curlers and hairpins.

35 The permeable sheets of this invention can be cloth or paper. The sheets should be of a material which will be inert toward the keratin-reducing composition. It has been found that materials such as wool, woolen flannel, felt, and cellulose acetate will react with mercaptans or alkaline materials and are, therefore, generally unsuitable. Cellulose materials such as paper made from purified flax or cloth made from purified cotton (batiste) have 45 been observed to be substantially inert toward mercaptans and alkaline materials and are suitable in other respects.

The sheets should be sufficiently porous to permit passage through the sheets of the aqueous solution used to dissolve the keratin-reducing composition, and also to permit passage through the sheets of subsequent rinsing solutions or other solutions used to restore the disulfide linkages. The sheets should not be so absorbent that the passage of solutions through the sheets is unduly inhibited.

50 This permeability can be achieved by using a loosely woven structure where there is spacing between the individual fibers. Cloth or paper of the non-woven type may also be used. If the sheets are closely woven or do not possess sufficient inherent permeability they may be 55 provided with a plurality of perforations.

60 The sheets should be of such a size and shape that they can at least partially encircle tresses of hair. The sheets may be long enough to extend the entire length of hair tresses or may only cover the ends of hair tresses in the manner of so-called "end wraps."

65 The sheets should be between about .005 and about .0005 inch thick before impregnation. Sheets thinner than about .0005 inch, regardless of the type of material, are too weak to handle and process. It has been observed 70 that sheets thicker than about .005 inch are too thick and bulky to be handled and processed easily and do not result

in the desired pliability and permeability characteristics after impregnation.

The keratin-reducing composition with which the sheets are impregnated must be substantially non-volatile. This prevents evaporation of the composition prior to use of the sheets and also reduces the odor of the mercaptans and alkaline agents. The composition should also be water-soluble in order that it can be activated by merely contacting the sheets with water.

The keratin-reducing composition contains a water-soluble, substantially non-volatile mercaptan selected from the mercapto-alkanoic acids, mercapto-acetic acid, mercapto-propionic acid, mercapto-butyric acid and mercapto-caproic acid and the water-soluble salts thereof. Examples of suitable mercaptans which are operative in the invention are thioglycolic acid, sodium thioglycoate, potassium thioglycolate, monoethanolamine thioglycolate, β -mercaptopisobutyric acid, thiohydracrylic acid, β -mercaptop-n-butyric acid, α -mercaptopcaproic acid, and thioglycolic acid.

It has been found that the amount of mercaptan present in the sheets of this invention should be in an amount equivalent to from about .003 gram to about .020 gram of thioglycolic acid per square inch of sheet. If mercaptan equivalent to less than about .003 gram of thioglycolic acid per square inch is present, a satisfactory wave will not be formed. If mercaptan equivalent to more than about .020 gram of thioglycolic acid per square inch is present, the hair structure may be damaged.

Although this range has been found critical for the cold waving of an average amount of ordinary hair in the usual sized hair tress, and is therefore essential to the production of waving materials intended for general use, it must be appreciated that this range can be modified to include the amount of mercaptan to safely wave varying sizes and types of hair. Moreover, the amounts of mercaptan useful for safely and effectively waving hair vary somewhat with the time the mercaptan is in contact with the hair, i. e., lesser concentrations of mercaptan require a longer contact time to reduce hair, but the risk of hair damage is much less than when higher concentrations of mercaptan which reduce the hair more rapidly are employed. The above-mentioned range is based on the usual, practical hair-waving periods.

In addition to the mercaptans it may be desirable to include in the keratin-reducing composition a water-soluble disulfide of the mercaptan used such as dithiodiglycolic acid, dithiodilactic acid, the disulfides of β -mercaptop butyric acid, β -mercaptopisobutyric acid or α -mercaptopcaproic acid, dithiodihydracrylic acid or a water-soluble salt of these to protect against excessive reduction and damage of the hair, in accordance with the disclosures in U. S. Patent 2,719,814 issued to Haefele and U. S. Patent 2,719,815 issued to Sanders on October 4, 1955.

During the time that the keratin-reducing composition is in the form of a solution in contact with the hair it is preferable that the pH be maintained between 8.5 and 10. This is accomplished by the presence of a substantially non-volatile alkaline buffering material as a component of the keratin-reducing composition with which the sheets are impregnated. The alkaline buffering material should not react unfavorably with the hair or with the components of the keratin-reducing composition.

The alkaline buffering materials commonly used in hair waving lotions such as ammonia, methylamine and ethylamine were found to be unsuitable for processing, storage and use of the impregnated sheets because they are too volatile. Inorganic alkaline materials with the exception of carbonates and bicarbonates proved to be unsuitable as alkaline buffering materials. Most inorganic alkaline materials such as the borates and the alkaline hydroxides can initially provide a suitable pH for hair waving, but they are not able to buffer, i. e., maintain a substantially constant pH, throughout the chemical

changes in the waving compositions during the treatment of the hair.

It was found that sodium or potassium carbonate provide a suitably constant pH when they are used as the alkaline material in the keratin-reducing composition impregnated in the sheets of this invention. However, these carbonates were observed to have other characteristics which make them unsuitable for use in the impregnated keratin-reducing composition of the sheets of this invention. Carbonates have a tendency to lose carbon dioxide on standing or heating and thus increase the alkalinity. The greatest difficulty encountered when attempting to use carbonates as alkaline buffering agents for the impregnated sheets of this invention is that the brittleness, that results from the crystalline character of the carbonates, causes the sheets to crack and break. Impregnated sheets using carbonates as alkaline agents can not easily be manipulated in hair waving nor can they be processed on the manufacturing machinery. This problem can not readily be remedied by the use of moisture or plasticizers in the sheets.

However, it was found that certain organic alkaline agents, i. e., certain substantially non-volatile hydroxyamines, have outstanding chemical and physical properties when used in the keratin-reducing composition of the impregnated sheets of this invention. They are excellent alkaline buffers for hair-waving purposes. Such hydroxyamines do not impart a brittle crystalline character to the impregnated sheets. In fact, they are waxy, i. e. solid to viscous-liquid in nature when impregnated in the sheets. The impregnated sheets, therefore are easily processed on machinery and are very pliable in use.

The hydroxyamines suitable for use in this invention are of the formula:

wherein X is selected from the group consisting of hydrogen and alkylol radicals containing 1 to 3 carbon atoms, R' and R'' are each selected from the group consisting of hydrogen, alkyl radicals containing 1 to 3 carbon atoms and alkylol radicals containing 1 to 3 carbon atoms and R''' is an alkylol radical containing 1 to 3 carbon atoms.

The hydroxyamines which have been found to be especially suitable in the impregnated sheets of this invention are:

Monoethanolamine

Trishydroxymethylaminoethane

2-amino-2-methyl-1,3-propanediol

Examples of other suitable hydroxyamines are:

Diethanolamine

amount of potassium dithiodiglycolate. The alkaline material was added after this reaction was complete.

	Percent
Potassium thioglycolate	22.0
Potassium dithiodiglycolate	10.5
Trishydroxymethylaminomethane	16.5
Water	51.0

A paper made from purified flax, "Ecusta #527," weighing 32 grams per square meter, about .0025 inch thick and 32 inches wide, was run through the above solution from rolls at a rate of about 50 yards per minute. The paper was gently squeezed between rolls, scraped with angle bars and then continuously dried in an oven. The sheets were slit into 3 inch widths and cut into 3 inch squares and had the following approximate composition:

	Percent
Paper	47
Potassium thioglycolate	22
Potassium dithiodiglycolate	11
Trishydroxymethylaminomethane	15
Moisture	5

When these sheets were used to wrap hair tresses which were then wound about hair curlers and saturated with water, the impregnated composition dissolved and reduced the hair substantially as shown in Example I. After rinsing and neutralization with an aqueous solution of sodium perborate, an excellent hair wave resulted from treatment with the acid of the impregnated sheets of this example.

Amounts of thiohydrylic acid, α -mercaptopropionic acid and β -mercaptop-n-butyric acid and their corresponding disulfide equivalent in keratin-reducing power to the amounts of potassium thioglycolate and potassium dithiodiglycolate shown in this example can be used in place of these salts with substantially equal results. Moreover, amounts of diethanolamine, 2-amino-1-butanol, 2-amino-2-methyl-1-propanol and monoisopropanolamine equivalent in alkalinity to the amount of trishydroxymethylaminomethane shown in this example can be used in place of this alkaline buffering agent with substantially equal results.

Example III.—Sheets impregnated with the following ingredients were produced by dipping the paper into an aqueous solution of these ingredients and drying the impregnated sheets to about 5% moisture. The sheets were used to obtain excellent hair waves in the manner described in Example II above.

The paper used was made from purified flax, "Ecusta #500," was about .0012 inch thick and weighed about 16 grams per square meter. The sheets were cut into 3 inch squares and had the following weights of impregnated ingredients:

	Grams
A. Thioglycolic acid present as the potassium salt	.04
Dithiodiglycolic acid present as the potassium salt	.02
2-amino-2-methyl-1,3-propanediol	.03

	B	C	D
Thioglycolic acid present as the potassium salt	.05	.06	.07
Dithiodiglycolic acid present as the potassium salt	.025	.030	.035
Trishydroxymethylaminomethane	.05	.06	.07

Sheets B, C, and D illustrate how increasing quantities of mercaptan can be used to obtain stronger hair waving action or shorter hair waving time. These sheets also illustrate that the quantity of alkaline agent is ordinarily increased with increasing mercaptan content. The protective dithiodiglycolic acid is ordinarily about half the amount of thioglycolic acid. On a square inch basis a

preferred composition range of sheets impregnated with the above ingredients is about as follows.

	Grams
Thioglycolic acid present as potassium salt	.005 to .008
Dithiodiglycolic acid present as the potassium salt	.0025 to .004
Trishydroxymethylaminomethane	.005 to .008

The preferred ratio by weight of the above ingredients is about 2:1:2 in the order listed. The preferred thickness of sheet material before impregnation is in the range of about .001 to about .003 inch.

Example IV.—To determine the range of mercaptan which can be impregnated in the sheets of this invention to obtain a satisfactory wave without damaging the hair, paper made from purified flax was impregnated with trishydroxymethylaminomethane and the potassium salts of thioglycolic acid and dithiodiglycolic acid by dipping the paper into an aqueous solution of these ingredients, drying the paper to about 5% moisture and cutting them into 3 inch square sheets. The papers were used to wave tresses of hair in accordance with the method previously described.

To determine damage to the hair tresses the standard 20% index test described in U. S. Patent 2,719,815 issued to J. H. Sanders on October 4, 1955 was used.

To determine the degree of wave, the wave grade photoscale shown in the drawing was used. The photoscale comprises nine wet switches of hair which had been cold waved to varying degrees of tightness in approximately a linear relationship by adjusting either the time of waving, strength of the waving lotion or both. The switches were made from the same type of ordinary human hair. The switches were six free inches in length, 36 millimeters wide at the top and weighed 2 grams. All the switches were wound on a 4 millimeter diameter mandrel during their cold waving. Arbitrary values from 0 to 8 have been assigned to the switches ranging from no wave (0) to overwave (8).

The paper, before impregnation, had the following thicknesses and weight:

	Paper	Thickness, inches		Weight in Grams Per Square Meter
		A	B	
45	A			.0012
	B			.0018
	C			.0025
				16
				24
				32

Paper	Grams Per 3" x 3" Square Sheet			Wave Grade	20% Index	Result
	Thioglycolic Acid ¹	Dithiodiglycolic Acid ²	Trishydroxymethylaminomethane			
50	.0183	.0092	.0183	2.75	.90	Under-waved.
	.027	.0135	.027	2.75	.92	Do.
	.212	.106	.212	6.0	.71	Damaged.
	.0235	.0118	.0235	2.5	.91	Under-waved.
55	.028	.014	.028	3.0	.84	Good wave.
	.0365	.0483	.0965	5.0	.85	Do.
	.17	.085	.17	5.25	.80	Do.
	.018	.009	.018	2.0	.91	Under-waved.
60	.019	.0095	.019	2.25	.92	Do.
	.001	.0455	.091	4.6	.85	Good wave.
	.19	.095	.19	5.5	.71	Damaged.
65						

¹ Potassium thioglycolate calculated as thioglycolic acid.

² Potassium dithiodiglycolate calculated as dithiodiglycolic acid.

70 Through experience it has been found that a satisfactory wave must have a wave grade of about three or greater but less than eight and that a non-damaging wave must have a 20% index of about .80 or greater. Therefore, from the above data and the previous examples it was determined that a satisfactory and safe range of mer-

5

2-amino-2-ethyl-1,3-propanediol

2-amino-1-butanol

2-amino-2-methyl-1-propanol

Monoisopropanolamine

Sufficient alkaline materials should be included in the keratin-reducing composition which is impregnated in the sheet to maintain a pH in the range of 8.5 to 10 while the composition is in solution and is in contact with the hair tress. The pH within these ranges, for optimum hair waving, is determined by the concentration of mercaptan in the composition and the time selected for the waving process. The time of waving has been described as being shorter with higher concentrations of mercaptan and longer with lower concentrations of mercaptan. The time of waving is also less at higher pH values and longer at lower pH values. Moreover, effective waving can be done at lower pH values if the concentration of the mercaptan is increased. If the concentration of the mercaptan is decreased the pH values should be higher to obtain effective waving action. It has been found that the concentrations of the substantially non-volatile hydroxyamine alkaline materials of this invention, especially monoethanolamine, trishydroxymethylaminomethane and 2-amino-2-methyl-1,3-propanediol, easily can be adjusted to the optimum pH for a particular mercaptan concentration and a corresponding waving time.

The concentration of the mercaptan and alkaline buffering material in the impregnated sheets should be adjusted so that, by adding water to make a solution of the compounds, a satisfactory hair wave is obtained during a given time of application without damage to the hair within the desired pH range by providing that higher concentrations of mercaptan are used at lower pH values and lower concentrations of mercaptan are used at higher pH values. For example, when a satisfactory hair wave is safely obtained with a given amount of thioglycolic acid at a pH of 9.2, it takes about one and a half as much at a pH of 8.9 and about two thirds as much at a pH of 9.5 to safely obtain approximately the same wave.

Additional materials can be added to the keratin-reducing composition on the sheets, such as lanolin, lanolin derivatives, perfume, wetting agents, dyes, binders and plasticizers, but these materials are not essential to the invention described herein.

The sheet material may be conveniently impregnated by use of a water solution of the keratin-reducing composition. The sheet material may be passed through the water solution, or the solution may be brushed or sprayed onto the sheet material. The impregnated sheet is then dried by means of an air blast, drum dryer, oven, or other suitable means to remove excess moisture. If too much water is removed, the sheet material may tend to crack or break, and it has been found that the presence of at least about 2% moisture is necessary to keep the sheets pliable and keep them from becoming brittle

6

and cracking and breaking in the processing machinery and when manipulated by the user. Since care must be taken during the drying step to prevent decomposition of the mercaptans and alkaline agents, for example by excessive heating, a lower limit of about 2% moisture is also desirable in this respect.

It has been found that excessive moisture in the impregnated sheets unduly encourages oxidation of the mercaptan to the disulfide if the sheets are left exposed to the air. This reduces the waving effectiveness of the sheets. It has been found that up to about 10% moisture in the sheets will allow very satisfactory stability in air for a length of time equal to average life before use.

15 The impregnated material in sheets of this invention containing more than about 10% moisture tends to rub off on the hands during use. It has been found that if the sheets contain greater than about 10% moisture they are also too messy for practical use. This condition tends 20 to reduce some of the outstanding advantages of the sheets of this invention including their simplicity, lack of messiness and lack of irritation to the hands. Moreover, excessively moist sheets tend to stick together and greatly reduce the ease with which they ordinarily can be 25 handled and used.

In order to prevent volatilization during drying, perfume, if employed, is preferably added to the sheet material after the drying step is completed.

The following examples will illustrate the invention 30 with greater particularity, but it is not limited thereto. Parts and percentages are by weight.

Example I.—An aqueous solution was prepared containing the following materials:

	Percent
35 Sodium thioglycolate	15.15
Sodium dithiodiglycolate	11.40
Monoethanolamine	9.45
Water	64.00

40 A continuous strip of paper made from purified flax, "Ecusta Type 234" was passed through this solution. The paper was three inches wide and 0.002 inch thick, and was provided with perforations $\frac{1}{32}$ inch in diameter uniformly spaced in a pattern containing 42 perforations per square inch. After the paper had passed through the 45 aqueous solution it was air-dried in a drying tunnel. After the drying step was completed the paper was cut into strips three inches long. The material incorporated in each 3 inch by 3 inch impregnated sheet weighed about .093 gram and had the following composition.

	Percent
Sodium thioglycolate	39.5
Sodium dithiodiglycolate	30.0
Monoethanolamine	25.0
Water	5.5

The hair of a test subject was washed and towel-dried. The hair was divided into tresses, and a single impregnated sheet was wrapped around each tress extending

60 from the end of the tress toward the scalp. Each wrapped tress was then wound on a curler and secured. When all the tresses had been wound, all were saturated with water. After waiting 15 minutes the hair was rinsed thoroughly with water. After an additional 30 minutes the hair was 65 neutralized with an aqueous solution of sodium perborate monohydrate acidified to a pH of 5.7. The hair was again rinsed with water, removed from the curlers, set in a normal fashion, and dried. A uniformly soft wave was obtained.

70 Similar results can be obtained by substituting monoethanolamine thioglycolate and dithiodiglycolate for the sodium salts in the above example.

Example II.—An aqueous solution having the following composition was prepared by mixing potassium thiogly-

75 colate with enough hydrogen peroxide to obtain the stated

captan equivalent to thioglycolic acid in the impregnated sheets is from about .003 to about .020 gram per square inch.

In any of the foregoing examples the dithiodiglycolates can be omitted from the keratin-reducing compositions impregnated in the sheets without reducing the advantages and the effectiveness of the sheets. The effect of such omission merely would require a more careful gauging by the user of the sheets, of the time that the impregnated sheet can be left in contact with the hair without the risk of hair damage.

It is to be understood that the action on the hair of the mercaptan in the keratin-reducing composition impregnated in the sheets of this invention can be neutralized by chemical compounds such as bromates, perborates, or hydrogen peroxide, or by the action of air alone.

The application is a continuation-in-part of my copending application Serial No. 550,469, filed December 1, 1955 now abandoned.

What is claimed is:

1. As an article of manufacture useful in cold waving hair, a permeable, pliable sheet impregnated with a substantially non-volatile, water-soluble, keratin-reducing composition, said composition containing a mercaptan selected from the group consisting of mercapto-acetic acid, mercapto-propionic acid, mercaptobutyric acid, mercapto-caproic acid and water-soluble salts of these distributed throughout said sheet in an amount equivalent to from about .003 to about .020 gram of thioglycolic acid per square inch of said sheet and sufficient substantially non-volatile, hydroxyamine alkaline material to maintain said composition within a pH range of 8.5 to 10 when said composition is in solution and in contact with the hair said hydroxyamine having the formula

wherein X is selected from the group consisting of hydrogen and alkyl radicals containing 1 to 3 carbon atoms, R' and R'' are each selected from the group consisting of hydrogen, alkyl radicals containing 1 to 3 carbon atoms and alkyl radicals containing 1 to 3 carbon atoms and R''' is an alkyl radical containing 1 to 3 carbon atoms, the concentration of mercaptan and said alkaline material being adjusted to obtain a hair wave during a given time of application without damage to the hair by having the concentration of mercaptan in the higher portion of said thioglycolic acid range for a lower pH within said pH range and having the concentration of mercaptan in the lower portion of said thioglycolic acid range for a higher pH within said pH range, said sheet being between about .005 and about .0005 inch thick before impregnation, being inert toward said composition and containing from about 2% to about 10% moisture.

2. The article of manufacture according to claim 1 wherein the hydroxyamine alkaline material is selected from the group consisting of monoethanolamine, trishydroxymethylaminomethane and 2-amino-2-methyl-1,3-propanediol.

3. The article of manufacture according to claim 2 wherein the mercaptan is monoethanolamine thioglycolate.

4. The article of manufacture according to claim 2 wherein the mercaptan is sodium thioglycolate.

5. The article of manufacture according to claim 2 wherein the mercaptan is potassium thioglycolate.

6. As an article of manufacture useful in cold waving hair, a permeable, pliable sheet impregnated with a keratin-reducing composition consisting essentially of about .005 to about .008 gram of thioglycolic acid present as the potassium salt, about .0025 to about .004 gram of

dithiodiglycolic acid present as the potassium salt and about .005 to about .008 gram of trishydroxymethylaminomethane per square inch of said sheet, said ingredients having the ratio by weight of about 2:1:2, said sheet being paper made from purified flax and about .001 to about .003 inch thick before impregnation and containing from about 2% to about 10% moisture.

7. The method of imparting a wave to hair without the use of heat which comprises the steps of forming the hair into tresses, wrapping about each tress a permeable, pliable sheet containing from about 2% to about 10% moisture, said sheet being impregnated with a substantially non-volatile, water-soluble, keratin-reducing composition, said composition containing a mercaptan selected from the group consisting of mercapto-acetic acid, mercapto-propionic acid, mercapto-butyric acid, mercapto-caproic acid and water-soluble salts of these distributed throughout said sheet in an amount equivalent to from about .003 to about .020 gram of thioglycolic acid per square inch of said sheet and a substantially non-volatile hydroxyamine alkaline material, said hydroxyamine having the formula

wherein X is selected from the group consisting of hydrogen and alkyl radicals containing 1 to 3 carbon atoms, R' and R'' are each selected from the group consisting of hydrogen, alkyl radicals containing 1 to 3 carbon atoms and alkyl radicals containing 1 to 3 carbon atoms and R''' is an alkyl radical containing 1 to 3 carbon atoms, winding each wrapped tress about a curler, said moisture range in said sheet resulting in a lack of messiness during use, saturating each tress with water whereby said keratin-reducing composition is dissolved and thereafter neutralizing the action on the hair of said keratin-reducing composition, said alkaline material being sufficient to maintain said composition within a pH range of 8.5 to 10 when said composition is in solution and in contact with the hair, the concentration of said mercaptan and said alkaline material in said sheet being adjusted to obtain a hair wave during a given time of application without damage to the hair by having the concentration of mercaptan in the higher portion of said thioglycolic acid range for a lower pH within said pH range and having the concentration of mercaptan in the lower portion of said thioglycolic acid range for a higher pH within said pH range.

8. The method according to claim 7 wherein the hydroxyamine alkaline material is selected from the group consisting of monoethanolamine, trishydroxymethylaminomethane and 2-amino-2-methyl-1,3-propanediol.

9. The method according to claim 8 wherein the mercaptan is monoethanolamine thioglycolate.

10. The method according to claim 8 wherein the mercaptan is potassium thioglycolate.

11. The method according to claim 8 wherein the mercaptan is sodium thioglycolate.

12. As an article of manufacture useful in cold waving hair, a permeable, pliable sheet impregnated with a substantially non-volatile, water-soluble, keratin-reducing composition, said composition containing a water-soluble salt of mercapto-acetic acid distributed throughout said sheet in an amount equivalent to from about .003 to about .020 gram of thioglycolic acid per square inch of said sheet and 2-amino-2-methyl-1,3-propanediol in amount to maintain said composition within a pH range of 8.5 to 10 when said composition is in solution and in contact with the hair, the concentration of the salt and the amine being adjusted to obtain a hair wave during a given time of application without damage to the hair by having the concentration of salt in the higher portion of said thioglycolic acid range for a lower pH within said

11

pH range and having the concentration of salt in the lower portion of said thioglycolic acid range for a higher pH within said pH range, said sheet being between about .005 and about .0005 inch thick before impregnation, being inert toward said composition and containing from about 2% to about 10% moisture.
